CLAIM

(57) The ornamental design for a hexagonal air hockey table, as shown and described.

DESCRIPTION

FIG. 1 is an exploded perspective view of a hexagonal air hockey table showing my new design, shown in its environmental use;

FIG. 2 is a top plan view thereof;

FIG. 3 is a bottom plan view thereof;

FIG. 4 is a front elevation view thereof, the rear elevation being a mirror image thereof; and,

FIG. 5 is an exploded perspective view thereof.

The broken lines showing of table legs indicate disclaimed portions and form no part of the claimed design. It is understood that the small holes on the top surface, which are shown partially and repeated throughout the whole top surface.

1 Claim, 3 Drawing Sheets*Fig. 3*

Fig. 4
